UNITED STATES PATENT OFFICE

HENRI JULES GUIRAUD, OF VEUXHAULLES, FRANCE, ASSIGNOR TO SOCIETE ANONYME LA COOPERATION AGRICOLE & INDUSTRIELLE, OF VEUXHAULLES, FRANCE

CARBURETOR

Application filed November 12, 1926, Serial No. 148,078, and in France October 12, 1926.

The invention has for its object to provide improvements in carburetors for all types of explosion motors but more particularly for low horse power motors such as are commonly used upon motorcycles.

A main feature of the invention consists in the combination of a piston sliding transversely to the suction conduit and used to throttle the mixture passage section towards the motor, with a flexible extension tube of the slow speed nozzle as described in pending application for patent Serial No. 40,560 filed by Claudel on June 30, 1925, this piston being suitably notched to cooperate with said flexible extension tube so that the latter, by altering its shape according to the various positions of the piston, operates substantially as described in the aforesaid patent application.

20 The annexed drawings show as exemplification one embodiment of the carburetor according to the invention. Fig. 1 is a vertical section through the common axis of the emulsion supply nozzle and the suction conduit of the motor. Fig. 2 is a partial section and partial plan view through line II—II of Fig. 1. Fig. 3 shows the carburetor in vertical elevation with parts thereof in section through line III—III of Fig. 2.

30 Fig. 4 is a side elevation seen from the right to the left in regard to Figs. 1 and 2.

The liquid fuel supplied by the calibrated plug 21 enters the diffusing tube 8, for normal operation, through channels 4 and 31, and the diffusing tube 7, for slow speed operation, through channels 4, 28 and 29.

The emulsion air arrives into both annular chambers around said tubes 7 and 8 by the conduits 32 and 33 shown in dotted lines (Fig. 3) and opening at 34 (Fig. 1), and enters said tubes through orifices 35 and 36.

The emulsion made in the diffusing tube 8 passes through the main nozzle 12 and springs out through the orifices 14. The emulsion made in the diffusing tube 7 passes through the slow speed nozzle 15 extending beyond the main nozzle 12 by means of a flexible tube 16. The output of the latter 50 can be regulated by a screw 17 which may

be hollow as described in the pending application for Patent Serial No. 40,560 filed by Claudel on June 30, 1925. The main air enters the mixing chamber by suitable ports 20 provided in the housing around the emulsion supply nozzles.

The mixture supplied to the motor is regulated by a throttling device as described hereafter which presents the main feature of the invention.

A piston 45 mounted for sliding movement within a cylinder guide 46, is operated by suitable means such as a Bowden cable 47 acting against the pressure of a return spring 48; this piston may thus be moved transversely within the conduit 19 so as to throttle more or less, as desired, the free passage section for the mixture towards the motor. In the piston portion opposite the driving cable I provide a slot 49 for the passage of the flexible extension tube 16 of the slow speed nozzle; the bottom part 50 (Fig. 1) of this slot is longitudinally curved so that in the closed position of the throttle the flexible tube due to its elasticity adapts itself within said curved slot whereby its free end is placed in front of the regulating screw 17. By opening the throttle 45 the tube 16 returns automatically into its axial position centrally to the gaseous vein. In this manner I obtain a simple and cheap throttling device in combination with a flexible tube for the supply of the slow down emulsion which will operate under all conditions.

It is well understood that without departing from the scope of the invention the throttling device can be adapted to carburetors of various types different from those described.

Claims:

1. In a carburetor with a mixing chamber, a main nozzle and a slow speed nozzle, in combination, a flexible tube extending the slow speed nozzle and parallel in its free position to the axis of the mixing chamber of the carburetor and a throttling piston moving in said mixing chamber transversely to the axis thereof and having an end parallel to said axis of the mixing chamber, the end of said

piston being provided with a groove of progressively increasing depth approaching the slow speed nozzle and adapted to receive said flexible tube.

- 5 2. In a carburetor with a mixing chamber, a main nozzle and a slow speed nozzle, in combination, a flexible tube extending the slow speed nozzle and parallel in its free position to the axis of the mixing chamber of the carburetor, a throttling piston moving in said mixing chamber transversely to the axis thereof and having an end parallel to said axis of the mixing chamber, the end of said piston being provided with a groove having parallel sides and of progressively increasing depth approaching the slow speed nozzle, a spring normally moving said piston into closed position and a control device attached to said piston for varying the position thereof against the action of said spring.
